UNITED STATES PATENT OFFICE.

ROBERT L. PARKER AND HERBERT D. FIELD, OF EL PASO, TEXAS, ASSIGNORS TO ROBERT C. RUSSELL, OF PITTSBURGH, PENNSYLVANIA.

CARD FILING SYSTEM.

Application filed February 3, 1922. Serial No. 533,848.

This invention relates to card index systems of the kind wherein a series of cards or index elements are suspended in overlapping relation on a suitable frame. The invention has to do particularly with the method of attaching a transparent covering to the lower exposed edge of each card to prevent the edges from becoming dirty, soiled, and in addition to prevent bending or dog-earing of the corners. This covering and reinforcement serves also to keep the cards in perfect alignment and to overcome certain objections to present methods of protecting these edges and the necessity of folding the edge of the card to support the covering in position, and to eliminate the bulky nature of the attachment of said covering to the card where engaging tongues or sockets are used.

Fig. 1 is a face view of the improved construction with the lower edge covering in place.

Fig. 2 is a fragmentary detail of a corner of Fig. 1 on a larger scale.

Fig. 3 is a fragmentary corner of one of the cards with holes punched to receive the sheath.

Fig. 4 is an enlarged vertical section of Fig. 2 along the line 4-4 looking in direction of the arrows.

Fig. 5 is an enlarged vertical cross section of Fig. 2 taken along the line 5-5.

Figs. 6 and 7 are vertical sections showing modifications.

Referring to the drawing, the card 1 is an index card of any suitable size which is supported by hinges 2 or other means fixed onto the top edge of the card and adapted to engage one of a series of hangers on a card frame not shown producing an overlapping arrangement. A plurality of cards are arranged upon the frame in overlapping relation so that a short portion of the lower or upper edge of each card is at all times visible. On this lower edge of each card is identifying printed or written matter which serves to identify the respective cards with the printed information thereon. It has been found with constant use that these cards tend to become frayed along their lower edges and dog-eared in a manner that is objectionable not only to the person making the entries upon the cards but the identifying or written matter along the bottom

edge of the cards becomes obliterated to such an extent that it cannot be read.

Numerous protecting sheaths or reinforcements have been devised to protect the card and the written matter thereon, but such attempts have not been altogether satisfactory due to the bulkiness of the assembly, and trouble experienced in keeping the protecting coverings from becoming disengaged from the ends of the cards.

This invention discloses a sheath or protective covering which when affixed to the edge of the card becomes almost an integral part thereof and is not easily detached from the card unless particular care is taken in disengaging the pawls or securing hooks from the punch holes of the card. The sheath takes the form of a transparent U-shaped member 3 which fits about the lower edge of each card and has a plurality of tongues 4 punched therein, which engage punch holes 5 in the card. In Figs. 4 and 5 the tongues appear as depending pawls 4a. In Fig. 4 the pawl is stamped from the front face of the sheath or covering and in Fig. 5 the pawl is stamped from the rear wall of the sheath, but in each case the pawls are inserted into the punch holes such as shown at 5 in Fig. 3. Both forms (Figs. 4 and 5) may be used with the same card, as shown, or either form may be employed, as desired. When it is desired to release the sheath or protective lower edge covering 3, it is only necessary to insert a blade, pencil point or other sharpened object through the aperture 6 and push out the pawl from engagement with the punch holes 5 in the card. The device as shown in Fig. 4 would require the disengaging aperture 6 to be cut in the back wall of the sheath, while in the construction shown in Fig. 5 the aperture 6 would necessarily be in the front, so that the engaging depending pawl 4a could be pushed out of the punch hole in the card. In Figs. 6 and 7 are shown modifications in which the engaging portion or locking of the sheath with the card is effected by means of hooks 7 formed in the back wall of the sheath and engaging the apertures 5 similarly to the depending pawls in Figs. 4 and 5. Similar detaching apertures 6 are cut in the front of the sheaths so that the hooks may be detached similarly to detaching of the pawls in Figs. 4 and 5.

In addition to the fact that the sheath or protective covering serves as a reinforcement for the lower edge of the card, it also provides a pocket into which a signal member 8 may be slid, different colored signal members of this type being used to identify the card for one reason or another in connection with the business in which the index system is used. In addition to the sheath 10 providing a means for inserting a signal member, the pocket may serve as a pocket for a strip extending completely across or part way across the lower edge of the card and containing printed matter relating to 15 the information contained upon the card, thus, either the signal or the identifying printed matter may be removed or replaced in the pocket as desired.

The construction provides reinforcement 20 and protection for the exposed edges of the overlapping cards, this protection occupying a minimum amount of space and adapted to be readily affixed or snapped into place and easily detached from the card. Also, 25 the printed or typewritten matter on both sides of the card, even to the extreme edge, can be easily read without removing the covering or removing the card from the pocket or detaching it from its hanger. 30 A further advantage of the construction is that the pawls or hooks which provide the locking feature, are cut directly from the material of the covering and no extra attachment is necessary. The punch holes

in the cards, into which the pawls or hooks 35 engage, are of a character similar to the apertures made for the insertion of the hangers and may be punched at the same time and in the same manner. The sheath extends upward on the card to a distance 40 slightly greater than the width of the exposed portion of the card when hung in position, but sufficiently greater to prevent catching on the next card above or below during the actual operation of lowering or 45 raising the card in making entries.

We claim as our invention:

1. A protecting sheath for the lower exposed edges of index cards comprising a U-shaped element of flexible transparent 50 material fixedly attached to the card by engagement of locking tongues formed in the sheath with apertures in the card, said sheath extending substantially the length of the exposed edge of the card forming a 55 pocket open at each end in combination with a signal strip slidably insertable in the open ends of the pockets.

2. A protecting sheath for the lower exposed edges of index cards comprising a 60 U-shaped element of flexible transparent material fixedly attached to the card adapted to form a pocket open at each end of the transparent sheath, in combination with an identifying strip slidably insertable in the 65 open-ended pocket.
